UNITED STATES PATENT OFFICE.

JOHN T. C. LOMBARDI, OF BROOKLYN, NEW YORK, ASSIGNOR TO HANSEN & LOMBARDI, A PARTNERSHIP COMPOSED OF EDWARD J. HANSEN AND JOHN T. C. LOMBARDI, BOTH OF BROOKLYN, NEW YORK.

COAL IGNITER.

Application filed January 30, 1924. Serial No. 699,432.

To all whom it may concern:

Be it known that I, JOHN T. C. LOMBARDI, a citizen of the United States of America, residing at Brooklyn, in the county of Kings 5 and State of New York, have invented certain new and useful Improvements in Coal Igniters, of which the following is a specification.

My invention relates to an apparatus and 10 a method for the lighting of a coal fire from under the grating of the stove.

My invention has for its object to furnish a flame of illuminating gas of sufficient heat intensity to ignite the coal from bottom 15 through the metallic grating on which the coal rests.

My invention has also for an object to thoroughly mix the air necessary for combustion with the gas before ignition in a 20 large and elongated mixing chamber, supported on adjustable legs and so proportioned that it will fit inside the ash chamber of an ordinary coal stove.

My invention has for further an object to 25 furnish an adjustable gas and air injector through which the gas and air are injected into the mixing chamber in proportions necessary for perfect combustion.

In the drawing:—
30 Figures 1 and 2 show the method and general arrangement for the lighting of a coal fire in a conventional coal stove.

Figures 3, 4 and 5 show the detail construction of the mixing chamber for gas 35 and air.

Figures 6 and 7 show the detail construction of the gas and air injector.

Referring to the drawing in which like reference characters designate corresponding 40 parts, 1 represents the stove in which the coal fire 2 is to be lit.

The gas and air mixing chamber 3 is placed in the ash chamber 4 below the metallic grating 5 and the supporting legs 6 45 are so adjusted that the proper distance is kept between the grating 5 and the mixing chamber 3.

A gas and air injector 7 supplied with an adjustable shutter 8 admits the air necessary 50 for perfect combustion into the mixing chamber 3 through the passage 9.

The injector 7 is supplied with a hose attachment 10 for the gas tube 11 which is connected to a convenient gas jet.

The gas duct 12 terminates in a reducing 55 nozzle 13 through which the illuminating gas will escape into the mixing chamber 3 with considerable velocity and in so doing will drag atmospheric air with it through the air passage 9 which is controlled by the 60 adjustable shutter 8.

On top of the mixing chamber 3 there is a row of small openings 14 each of which will become the source of a flame 15 when the gas is lit.

When ignition of a coal fire takes place through the metallic grating the intensity of heat has to be exceptionally high as a considerable amount of heat is carried away by the metallic grating.

In order to obtain an illuminating gas flame of sufficient heat intensity to overcome this loss of heat and also to rapidly light the coal fire it has been found necessary to thoroughly mix the proper amount 75 of air with the illuminating gas in an especially constructed air chamber 3 of spacious dimensions.

The mixing chamber 3 is an elongated hollow casting of triangular cross section.

The illuminating gas escapes into the mixing chamber 3 from the injector 7 in a manner diagrammatically shown in Figure 4.

The gas which enters through the narrow gas duct 12 at a high velocity escapes 85 through the flame holes 14 at a greatly reduced velocity as the total area of the flame holes 14 is much larger than the area of the gas duct 12.

The excess energy has been used up in 90 setting up whirls in the large mixing chamber 3 which causes a thorough mixing of the gas and air.

It is to be noted that the gas discharge 95 takes place at the most spacious part of the triangular cross section and the flame holes are provided at the narrowest part of the triangular cross section, viz, the top.

Thus before a sufficient pressure can be created to force the gas mixture up through the narrow top section and out through the flame holes a thorough diffusion will take place in the spacious bottom part said diffusion being materially assisted by the change of momentum which must take place 100 prior to the discharge through the lateral row of flame holes.

It is also to be noted that due to the trian-

2
gular cross section of the mixing chamber 3 the upwards flow of gas will increase the closer up the gas comes to the flame holes 14 and as an increased velocity is helpful for 5 the diffusion of gaseous mixtures the gas and air will be most thoroughly mixed just before they escape into the flames 15.

I do not desire to be understood as limiting myself to the specific details of construction and arrangement as herein described and illustrated, as it is manifest that variations and modifications may be made in the adaptation of the device to various conditions, without departing from the 10 spirit and scope of my invention.

I claim:—

1. A long and straight mixing chamber for illuminating gas and air having a triangular cross section, an end inlet through 20 which the gas escapes directly into said mixing chamber in a longitudinal direction at a high velocity dragging the air with it through passages in direct communication with the atmosphere, the gas mixture being free to 25 expand unobstructed longitudinally in said chamber causing whirls to be set up in the entire length of said elongated mixing chamber prior to the discharge through flame

holes provided at the apex of the triangular cross section. 30

2. A long and straight mixing chamber for illuminating gas and air having a cross section wider at the bottom than at the top an end inlet through which the gas escapes directly into said mixing chamber in a longitudinal direction at a high velocity dragging the air with it through passages in direct communication with the atmosphere, the gas mixture being free to expand unobstructed longitudinally in said chamber 40 causing whirls to be set up in the entire length of said elongated mixing chamber prior to the discharge through a row of flame holes provided in the narrow top part of said chamber. 45

3. A long and straight mixing chamber for illuminating gas and air having a triangular cross section and triangular ends, gas inlet located at the base of one of the triangular ends and flame holes located at the 50 top of the triangular section the outflow being at right angles to the inflow.

JOHN T. C. LOMBARDI.
